(57) **CLAIM**

The ornamental design for an overhead guard for a materials handling vehicle, as shown.

DESCRIPTION

FIG. 1 is a perspective view of an overhead guard for a materials handling vehicle taken from the left front of the vehicle, the forks defining the front of the vehicle;
FIG. 2 is a perspective view of the overhead guard of FIG. 1 taken from the right rear of the guard;
FIG. 3 is a plan top view of the overhead guard of FIGS. 1 and 2;
FIG. 4 is an elevational right side view of the overhead guard of FIGS. 1 and 2;
FIG. 5 is an elevational left side view of the overhead guard of FIGS. 1 and 2;
FIG. 6 is an elevational rear view of the overhead guard of FIGS. 1 and 2;
FIG. 7 is an elevational front view of the overhead guard of FIGS. 1 and 2; and,
FIG. 8 is a plan bottom view of the overhead guard of FIGS. 1 and 2.
